US0D1077055S

(12) **United States Design Patent** (10) **Patent No.:** **US D1,077,055 S**
(45) **Date of Patent:** **** May 27, 2025**

(54) **GAMING SERVICES ROBOT**

- (71) Applicant: **Aristocrat Technologies, Inc.**, Las Vegas, NV (US)
- (72) Inventors: **Victor Blanco**, Austin, TX (US); **Michelle Cupersmith**, Las Vegas, NV (US); **Rajendrasinh Jadeja**, Las Vegas, NV (US); **Frank Rodriguez**, Las Vegas, NV (US); **Charles Miller, Sr.**, Henderson, NV (US); **Akifusa Nakazawa**, Mountain View, CA (US); **Ariel Turgel**, San Francisco, CA (US); **Sy Hyin Wong**, San Jose, CA (US)
- (73) Assignee: **Aristocrat Technologies, Inc.**, Las Vegas, NV (US)

(**) Term: **15 Years**

(21) Appl. No.: **29/949,615**

(22) Filed: **Jun. 27, 2024**

(57) **CLAIM**

The ornamental design for a gaming services robot, as shown and described.

DESCRIPTION

FIG. 1 is a front perspective view of a gaming services robot showing our new design according to a first embodiment; FIG. 2 is a front elevation view thereof; FIG. 3 is a right-side elevation view thereof, with the left-side elevation view being a mirror image thereof; FIG. 4 is a rear elevation view thereof; FIG. 5 is a top plan view thereof; FIG. 6 is a front perspective view of a gaming services robot showing our new design according to a second embodiment; FIG. 7 is a front elevation view thereof; FIG. 8 is a right-side elevation view thereof, with the left-side elevation view being a mirror image thereof; FIG. 9 is a rear elevation view thereof; and, FIG. 10 is a top plan view thereof.

The dashed broken lines in the figures illustrate portions of the gaming services robot that form no part of the claimed design.

1 Claim, 10 Drawing Sheets

Related U.S. Application Data

continuation of application No. 29/752,251, filed on Sep. 25, 2020, now Pat. No. Des. 1,006,884.
